DESIGN FOR A KNITTED SWEATER

Bernard Sapin, New York, N. Y.

Application January 28, 1948, Serial No. 144,113

Term of patent 14 years

(Cl. D3—4)

To all whom it may concern:

Be it known that I, Bernard Sapin, a citizen of the United States of America, residing at New York, county of New York, and State of New York, have invented a new, original, and ornamental Design for a Knitted Sweater, of which the following is a specification, reference being had to the accompanying drawing, forming a part thereof.

The ornamental design for a knitted sweater, showing my new design;

Fig. 2 is a back view thereof;

Fig. 3 is a sectional view on the line 3—3 of Fig. 2.

I claim:

The ornamental design for a knitted sweater, substantially as shown.

BERNARD SAPIN.
